COMBINED AMPLIFIER HOUSING AND BASE FOR A RECORD PLAYER OR SIMILAR ARTICLE

Yoshiaki Iida, Osaka, Japan, assignor to Matsushita
Electric Industrial Co., Ltd., Osaka, Japan

Filed Feb. 12, 1970, Ser. No. 21,422

Claims priority, application Japan Oct. 20, 1969

Term of patent 14 years

Int. Cl. D14—04

U.S. Cl. D26—14

FIG. 1

FIG. 2

FIG. 3

FIG. 4

FIG. 5

FIG. 1 is a front, top and right side perspective view of a combined amplifier housing and base for a record player or similar article showing my new design;

FIG. 2 is a front elevational view,

FIG. 3 is a rear elevational view,

FIG. 4 is a top plan view, and

FIG. 5 is a left side elevational view thereof.

Portions of the drawing figures are shaded to indicate contrast in appearance, and portions are diagonally lined to indicate transparency.

I claim:

The ornamental design for a combined amplifier housing and base for a record player or similar article, as shown and described.
